UNITED STATES PATENT OFFICE.

MARTIN STIELER, OF CHICAGO, ILLINOIS.

CONCRETE-FORM.

1,164,319.

Specification of Letters Patent. Patented Dec. 14, 1915.

Application filed August 11, 1915. Serial No. 44,968.

To all whom it may concern:

Be it known that I, MARTIN STIELER, a citizen of the United States, and a resident of the city of Chicago, county of Cook, and 5 State of Illinois, have invented certain new and useful Improvements in Concrete-Forms, of which the following is a specification.

My invention relates to improvements in 10 concrete forms, and has for its object the provision of an improved construction of this character arranged to facilitate and expedite the building of concrete structures of various forms and shapes.

The invention consists in the combinations and arrangements of parts hereinafter described and claimed.

The invention will be best understood by reference to the accompanying drawings 20 forming a part of this specification, and in which,

Figure 1 is a vertical section showing a portion of a form embodying my invention, also a portion of a chimney as built by the 25 form, said figure being a section taken on line 1—1 of Fig. 5, Fig. 2, an enlarged elevation of a cable winding drum employed in the construction, Fig. 3, a section taken on line 3—3 of Fig. 2, Fig. 4, a side view of the 30 cable winding construction, Fig. 5, a partial horizontal section of the form, Fig. 6, an enlarged elevation illustrating the form of plates employed in the construction, Fig. 7, a section taken on line 7—7 of Fig. 6, Fig. 35 8, an enlarged section illustrating the method of attaching plates to their stiffening bars, and Fig. 9, an enlarged vertical section of an interior plate of the form, taken on line 9—9 of Fig. 5.

The preferred form of construction, as 40 illustrated in the drawings, comprises an outer and an inner form member, said members being arranged concentrically so as to form sections of the chimney. The outer form consists of a plurality of flexible sheet metal plates 10 outwardly offset at one edge 45 11 to rest loosely over the corresponding edges of the adjoining plates. Vertical stiffening bars 12 and 13 are secured to the outer side of each of the plates 10, the bar 50 12 being secured along the edge opposite said offset portion 11 and bars 13 being equally spaced across the body of the plate, as shown, there being three of the bars 13 55 employed. Each of the bars 12 is provided with a lateral extension 14 arranged to

overlap the corresponding portion 11 on the adjoining plate. The bars 12—13 are secured to the plates 10 by means of screw-bolts 15, the inner ends of the bolt-holes 60 through said bars being countersunk at 16, so that when the bolts are tightened in position, the corresponding portions of plate 10 will be drawn into said countersinks thus providing a secure connection between the 65 bars and the plates and providing a smooth inner surface on the plates, as shown in Fig. 8. Bars 12—13 are outwardly offset at their upper portions 17—18 and at their lower portions 19—20 and a plate 21 is mounted 70 under the upper offset portions, said plate being adapted to fit under the lower offset portions on the next plate above and thus constitute a bond between the plates at their tops and bottoms, as will be readily understood. The plates 11 are provided with 75 elongated slots 22 fitting the corresponding bolts 15 so as to permit of latitude of movement between the bars and the plates and thus permit of changes in curvature in 80 plates 10.

At one end each of the plates 21 is provided with a bifurcated extension 23 adapted to engage the corresponding bolt 24 on the adjoining plate thus effecting a good lateral 85 bond between the plates 10. Steps in the form of triangular loons 25 are secured to the outer sides of one of the bars 13 on each of the plates 10 and cables 26 are passed around the plates 10 immediately above the 90 steps 25 so as to hold the same in place, said steps 25 thus serving to properly position 95 the cables 26 and at the same time as means of supporting workmen on the exterior of the form. One end of each of the cables 26 is anchored to a bolt 27 secured between two angle irons 28 fastened to the outside of one of the plates 10. The other end of each of the cables 26 is angularly bent and passed through a perforation 29 in a winding drum 100 30 rotatably mounted between angle irons 28.

An eccentric clamping lever 31 is arranged in each of the drums 30 to clamp the corresponding end of the corresponding cable 26 in perforation 29 so as to prevent withdrawal of the same. Drum 30 carries a ratchet wheel 32 co-operating with a pawl 33 and a squared trunnion 34 by means of which said drum may be engaged and rotated by a wrench. By this arrangement, 110 the plates 10 may be nicely drawn and held in proper positions.

The interior portion of the mold is made up of plates 10 identical in all respects with the plates 10 in the exterior part of the mold except that hooks 35 are provided on the 5 bars 12-13 instead of steps 25. In this instance, the plates are secured in proper form by bars or rods 36 provided in the hooks 35 and overlapping at their ends, as shown.

10 In practice, a certain number of sections are made up and the concrete construction formed in the usual manner. Then additional sections are arranged above the other sections, the lowermost sections being removed 15 and the construction completed in this manner. The construction illustrated is shown as employed for constructing a chimney which has an upwardly tapering conical outer wall 37 and an inner wall 35 which flares slightly outwardly and upwardly. Owing to the flexibility of the plates 10 and the latitude for adjustment afforded, the form can be arranged to turn out a smooth and accurate construction such 25 as illustrated. When the exterior diameter decreases sufficiently, one plate 10 is omitted from the outer form, the latitude of adjustment of the plates permitting of this.

While I have illustrated and described 30 the preferred form of construction for carrying my invention into effect, this is capable of variation and modification without departing from the spirit of the invention. I, therefore, do not wish to be limited to the 35 precise details of construction set forth, but desire to avail myself of such variations and modifications as come within the scope of the appended claims.

Having described my invention what I 40 claim as new and desire to secure by Letters Patent is:

1. A concrete form comprising a plurality of plates offset and loosely overlapping at 45 their side edges; cables encompassing said plates; and means for tightening said cables, substantially as described.

2. A concrete form comprising a plurality of flexible plates offset and loosely overlapping at their side edges; cables encompassing said 50 plates; and means for tightening said cables, substantially as described.

3. A concrete form comprising a plurality of plates offset and loosely overlapping at their side edges; vertical stiffening bars on 55 said plates, said bars being outwardly offset at top and bottom; plates placed under said

outwardly offset bar portions; and means for holding said plates together, substantially as described.

4. A concrete form comprising a plurality 60 of flexible plates offset and loosely overlapping at their side edges; vertical stiffening bars on said plates, said bars being outwardly offset at top and bottom; plates placed under said outwardly offset bar portions; and means for holding said plates together, substantially as described.

5. A concrete form comprising a plurality 65 of plates offset and loosely overlapping at their side edges; vertical stiffening bars on 70 said plates, said bars being outwardly offset at top and bottom; plates placed under said outwardly offset bar portions; cables encompassing said plates; and means for tightening said cables, substantially as described.

6. A concrete form comprising a plurality 75 of flexible plates offset and loosely overlapping at their side edges; vertical stiffening bars on said plates, said bars being outwardly offset at top and bottom; plates placed under said outwardly offset bar portions; cables encompassing said plates; and means for tightening said cables, substantially as described.

7. A concrete form comprising a plurality 85 of flexible plates offset and loosely overlapping at their side edges; vertical stiffening bars on said plates, said bars being outwardly offset at top and bottom; plates placed under said outwardly offset bar portions; steps in the form of triangular loops 90 secured to said bars; cables encompassing said plates passing above said loops; and means for tightening said cables, substantially as described.

8. A concrete form comprising a plurality 95 of flexible plates offset and loosely overlapping at their side edges; vertical stiffening bars on said plates, said bars being outwardly offset at top and bottom; plates placed under said outwardly offset bar portions; a plurality of hook members secured 100 to the outer faces of said bars; and securing bars placed in said hooks, substantially as described.

In testimony whereof I have signed my name to this specification in the presence of two subscribing witnesses.

MARTIN STIELER.
